UNITED STATES PATENT OFFICE.

WILLIAM H. FISHER, OF CHICAGO, ILLINOIS.

GRAIN-DOOR.

982,261.

Specification of Letters Patent. Patented Jan. 24, 1911.

Application filed August 24, 1910. Serial No. 578,738.

To all whom it may concern:

Be it known that I, WILLIAM H. FISHER, a citizen of the United States, residing at Chicago, county of Cook, and State of Illinois, have invented certain new and useful Improvements in Grain-Doors, of which the following is a specification.

My invention relates to improvements in grain doors and has for its object the production of a door of this character which will be of durable and economical construction, one which may be readily and expeditiously arranged in operative position or removed to inoperative position, and one which will be efficient in use.

Other objects will appear hereinafter.

With these objects in view my invention consists in a grain door characterized as above mentioned and in certain details of construction and arrangement of parts all as will be hereinafter fully described and more particularly pointed out in the appended claims.

My invention will be more readily understood by reference to the accompanying drawings forming a part of this specification, and in which,

Figure 1 is a fragmentary side elevation of a grain car to which is applied a door embodying the preferred form of my invention, the door being shown arranged in operative position, Fig. 2 is an enlarged detail transverse section taken on line $x-x$ of Fig. 1. Fig. 3 is a fragmentary sectional view of the interior of the grain car showing the door arranged in inoperative position. Fig. 4 is a section on line $y-y$ of Fig. 3. Fig. 5 is a sectional view similar to Fig. 3 showing the door in operative position, the section being taken on line $z-z$ of Fig. 6. Fig. 6 is a section on line $w-w$ of Fig. 5, and Figs. 7 and 8 are enlarged sectional details taken on lines $v-v$ and $u-u$ respectively of Fig. 5.

Referring now to the drawings 1 indicates a grain car which may be of any ordinary or preferred design, 2 indicating the doorway thereof, and 3 the conventional sliding door for the latter. Arranged substantially centrally in the doorway 2 is a vertically extending metallic post 4, the latter being comprised of two elongate angle irons 5 the adjacent flanges of which are rigidly secured, preferably riveted together. The lower end of the post 4 is bifurcated as indicated to form a substantially rectangular

smaller passageway 2'. The lower extremity of the post 4 is held in position by virtue of the lower extremities of the members 5 thereof engaging spaced slots 6 provided in the guard plate 7 which is, as is known, ordinarily provided at the base of a railway car doorway. In order to permit of such engagement of the lower extremities of the members 5 the inwardly extending flanges of the latter are cut away as indicated. The upper extremity of said post is secured to the upper bar of the frame of the doorway by means of a headed pin 8 which engages an elongated slot 9 provided in the upper extremity of said post. The slot 9 is of such a length, as will be observed, as to permit of sufficient vertical movement of the post 5 so as to effect disengagement of the lower extremity thereof with the slots 6. With the arrangement disclosed it will be seen that the upper extremity of the post 4 is held against outward movement by engagement or abutment of the inner side of the upper bar of the doorway frame, vertical movement of said post, when in operative position, being prevented by means of a flange 10 provided upon the outer side which is adapted to engage under said bar of said doorway. The pin 8 will be of such a length as to permit of inward movement of the upper extremity of the post sufficient to effect disengagement of the flange 10. When the car is filled with grain, the pressure of the latter upon the post 4 will serve to lock said post against inward movement and hence prevent disengagement of the flange 10 and vertical movement of said post.

Arranged in the doorway 2 at either side of the post 4 are door sections or closure members 11, the same being held in position against outward movement by reason of the inner vertical edges thereof resting against the vertical bars of the doorway frame. Provided upon the outer and inner sides of the sections 11 are reinforcing cleats 12 and 12' respectively, the former, when said door sections are in operative position, engaging against the inner sides of the vertical posts of the doorway frame to prevent outward movement of said door sections. Hinged at 13 to the upper edges of the sections 11 are inwardly swinging sections 14. Said sections 14, during the filling of a car with grain may be swung inwardly to afford sufficient opening above the same for admission

of the grain. Upon filling of the car said sections will be swung to vertical position and, in which position, the same will be held by the pressure of the grain thereon. 5 Pivotal secured as at 15 to the outer sides of one of each of the sections 11 and 14 is a strap 16. The straps 16 are adapted to extend around the outer sides of the post 4, when the door sections are in operative position, the free extremities thereof being slotted for engagement by the turn buttons 17 provided upon the other of the sections 11 and 14. When so arranged the straps 16 will evidently serve to lock the door sections 15 to the post 4, preventing inward movement thereof.

Secured upon the outer sides of the lower ends of the members 5 of the post 4 are angular guide members 18 which are adapted 20 to form guide channels for a closure plate 19 which is vertically slidable therein, the latter evidently serving as a closure for the opening or passageway 2'.

25 indicates a reinforcing angle iron which is secured upon the outer side of the closure 19, said angle iron also serving as a means of engagement for the hand to effect sliding movement of the closure.

Secured to and upwardly extending from 30 the closure 19 is a bar 21, the latter being provided with a plurality of spaced slots 22. Said slots are adapted to be engaged by a turn button 23 arranged in the post 4 and whereby the closure may be held at 35 various elevations as desired. Provided upon the outer edges of the door sections 11 are spaced eyes 24, whereby said sections may be supported in inoperative positions upon supporting hooks 25 arranged within 40 the car for that purpose. As indicated in Fig. 3 the post 4 may also be supported by one of the supporting hooks 25 in inoperative position together with the door sections 11. Unlawful removal of the door sections 45 is prevented by chains 26 which serve to lock the same, as indicated, to the car.

A door of a construction as set forth is durable and is simple of construction, the same may be readily and quickly arranged 50 in position for use, and as readily and quickly removed and arranged in inopera-

tive position. The provision of the opening 2' and the readily slidable closure 19 therefore affords means whereby the grain may be readily unloaded from the car without necessitating the removal of the sections 11. 55

While I have shown what I deem to be the preferable form of my grain door I do not wish to be limited thereto as there might be various changes made in the details of 60 construction and arrangement of parts described without departing from the spirit of the invention. I therefore do not wish to be limited to the exact details set forth but desire to avail myself of such changes 65 and alterations as fairly fall within the scope of the appended claims.

Having described my invention what I claim as new and desire to secure by Letters Patent is:

1. The combination with a car having a doorway, of a vertically extending post having a bifurcated lower end, said post being removably supported substantially central in said doorway; door sections resting 75 against said post and against the vertical frame posts of said doorway, the said door sections being cut away to form an opening registering with said bifurcated lower end; and a closure mounted upon the bifurcated 80 lower end of said post, substantially as described.

2. The combination with a car having a doorway, of a vertically extending post removably supported substantially central in 85 said doorway, said post consisting of two angle irons riveted together at their central and upper portions but spread apart at their lower ends to provide a discharge opening; door sections resting against said post, 90 said door sections being cut away to form an opening registering with said discharge opening; and a closure for said discharge opening, substantially as described.

In testimony whereof I have signed my 95 name to this specification in the presence of two subscribing witnesses.

WILLIAM H. FISHER.
